TUCKER

Hale Paxton, Redlands, Calif., assignor to Paxton Credit Corporation, Sanger, Calif., a corporation of California

Application February 13, 1931, Serial No. 515,509

3 Claims. (Cl. 1—10)

My invention relates to receptacle lidding devices and particularly to machines for applying lids to shipping cases.

In my copending application, Ser. No. 501,285, filed Dec. 10, 1930, I have disclosed an automatic box lidded which is especially adapted for applying lids to fresh fruit or vegetable shipping cases when the contents are heaped up above the top of the case in which is known as a "crown pack." A feature of that invention was embodied in means for automatically tucking the superposed contents of the box inward between the box and the lid as the latter is pressed into contact with the box to permit its ends to be nailed thereto. It is an object of my invention to provide a box lidded or cover press having an improved means for tucking the superposed contents of the box between the lid and the box during the application of the lid. It is a further object of my invention to provide such a tucking means which will be automatically operated by contact with the box.

The manner of accomplishing the foregoing objects as well as further objects and advantages will be made manifest in the following description together with the accompanying drawings, in which:

Fig. 1 is a front elevational view of an automatic box lidded embodying my invention.

Fig. 2 is a side elevational view of Fig. 1.

Fig. 3 is a fragmentary view similar to Fig. 1, and illustrating the operation of the aforesaid lidded.

Figs. 4 and 5 are enlarged detail sectional views taken on the lines 4—4 and 5—5 respectively of Fig. 2 and illustrating the operation of my invention.

Fig. 6 is a view similar to Fig. 4 illustrating in detail the parts of the invention in the same positions in which they are shown in Fig. 3.

Fig. 7 is a fragmentary detailed view of a modified form of tucker roller of my invention.

Referring specifically to the drawings, the illustrated embodiment of my invention comprises an automatic box lidded 25 having a frame 26 on which is mounted a box lifting conveyor 27, and on which is fixedly supported a lid applying mechanism 28.

The frame 26 includes angle footing members 30 which are connected by a solid steel bar 31 and from which heavy channel standards 32 extend upwardly and are connected together as by a horizontal frame member 35. Provided on forward faces of the standards 32 are slideways

38. Also secured on the standards 32 are box guides 42.

The conveyer

The box receiving conveyer 27 includes a framework 45 having inner and outer longitudinal members 46 and 47 connected rigidly by anvil bars 49 and 50. Rigidly connected to lower surfaces of the anvil bars 49 and 50 is a relatively heavy lifting bar 51. Secured to opposite ends of the longitudinal bar 46 are cylindrical 10 slide shafts 55. Extending downwardly from opposite ends of the bar 47 is a vertical bracing framework 56, opposite side members 57 of which extend downwardly, diagonally and are connected at their lower ends to the slide shafts 55. 15

Suspended from the anvil bars 49 and 50 by bolts 60 having compression springs 61 is a depressible roller conveyer frame 63. Provided on the frame 63 are conveyer rollers 68.

Secured in a suitable opening at a middle 20 point in the lower surface of the lifting bar 51 is a piston rod 70 of a hydraulic cylinder 71 which is disposed on a vertical axis and rests upon the solid frame cross bar 31.

Owing to the spring mounting of the frame 63 25 on the conveyer frame-work 45 the rollers 68 may be pressed downwardly as by a box 75 resting on the conveyer 27 until opposite ends 76 of the box will come to rest on the anvil bars 49 and 50. Provided on the conveyer 27 is a stop 30 78 which is adapted to halt a box 75 when this is rolled onto the conveyer 27 in a particular position for a purpose to be explained hereinafter. The stop 78 may be of any desired character and, while not illustrated as such in this case, it is 35 preferably arranged to operate in the same manner as the box stop mechanism 72 disclosed in my aforementioned copending application.

The lid applying mechanism

40

The lid applying mechanism 28 is supported upon a pair of plates 80 which are supported at their upper ends by the bar 35 and at their lower ends by lugs 81 provided on the frame standards 32. Forward ends of the plates 80 are U-shaped 45 so as to permit a strapping device such as shown in my copending application, Ser. No. 554,211, filed July 31, 1931, upon which Letters Patent of the United States No. 1,955,144 were granted April 17, 1934, to be incorporated with the lid 50 applying mechanism 28 should this be desired. Mounted on inner faces of each of the plates 80 is a series of nailing chucks 90 in each of which is operated one of a series of nailing plungers 91. Means (not shown) for operating these plungers 55 85

is provided on the upper ends of the standards 32. Also secured to the plates 80 is a pair of cover receiving and fruit tucking mechanisms 100.

The fruit tucking mechanisms

5 Each of the mechanisms 100 has a pair of supports 101 which are secured to the inner face of one of the plates 80 and to the lower end of which is secured a lid compressing bar 105. Extending into recesses in adjacent faces of the supports 101 is a shaft 106 of a cover receiving means 107 having a stem plate 108 which extends downwardly outside of the bar 105 and underneath this bar where it is provided with a cover latch 110. Each of the latches 110 has a cover supporting shoulder 111 from which a guide apron 112 extends downwardly. The forward end of each latch 110 is bent outwardly so as to guide into place a cover shoved between opposite latches 110 from the front of the lidding machine 25. Secured at opposite ends as by screws 115 to the supports 101 is a strap 116 having a tongue 117 formed centrally thereon which is bent downwardly and supports one end of a tension spring 118, the opposite end of which extends through suitable openings in the stem plate 108 so as to yieldably urge the latch 110 towards its inwardmost position.

30 The cover compressing bar 105 has a bevelled inner face 120 for a purpose which will become evident hereinafter. Opposite ends of this bar are provided with downwardly extending legs 121, each of which has a stop 122 extending inwardly therefrom. Secured to the upper face of the bar 105 are a pair of rearwardly extending fingers 123 the purpose of which will be made evident hereinafter.

35 Pivots supported between lower ends of the legs 121 is one of a pair of fruit tuckers 125. This tucker includes a pair of arms 126 each of which is pivotally secured to an inner face of one of the legs 121 as by a bolt 127. Each arm 126 extends downwardly and inwardly and these arms are provided with suitable apertures in their lower ends for pivotally receiving trunnions 129 of tucker rollers 130. Thus the roller 130 is pivotally supported between the arms 126 so as to be freely rotatable. In the preferred embodiment illustrated herein the roller 130 is shown, as formed of sections of pipe 134 provided with plugs 135 in their ends, from which plugs the trunnions 129 extend axially. Each pair of arms 126 is adapted to have their downward movement limited to the position in which they are shown in Figs. 1, 2 and 4, as by lugs 140 extending outwardly from upper extensions 141 provided on these arms. The lugs 140 bear against outer edges of the legs 121. This downward position of the arms 126 is reached when the lugs 140 come against outer edges of the legs 121. Yieldably urging each tucker 125 toward its downward position is a pair of tension springs 145 lower ends of which are secured to pins 146 on the extensions 141 of the arms 126, the upper ends of these springs being hooked into suitable eyes formed in the fingers 123.

40 The operation of my invention is as follows:

45 The automatic lidded 25 illustrated in the drawings is designed especially for use in lidding lettuce crates "crown packed" in the usual manner with the lettuce extending up above the top of the crate. The box 75 illustrated in the drawings represents a standard lettuce crate. Before packing lettuce in this crate, paper linings 160 are laid in the crate and after the lettuce is packed

50 in the box so that it is heaped up thereabove the linings 160 are folded over this lettuce.

The crates 75 are collected on an endless conveyer from which they are discharged one at a time onto the elevating conveyer 27 of the lidded 55 25, each box thus fed coming to rest against the stop 78 in the position in which it is shown in Fig. 1. While the crate 75 is thus moving into position a cover 165 is manually picked up from a stack and shoved into the lidded 25 between the 10 cover latches 110 so as to be supported by the shoulders 111 thereof. If it happens to be more convenient, the cover 165 may be first positioned underneath the tuckers 125 and see-sawed into place, first lifting one end and shoving it into 15 place against one of the latches 110 and then pushing this latch outwardly enough to permit the opposite end of the cover to be lifted straight upwardly and released into place supported on the shoulder 111 of the other latch 110.

20 The operator now actuates mechanism for supplying oil to the hydraulic cylinder 71 to cause this to lift the conveyer 27 and the filled crate 75 resting thereon. This operating mechanism, although not shown in this case, is illustrated in 25 my copending application, Ser. No. 554,213 filed July 31, 1931, upon which Letters Patent of the United States No. 1,947,917 were granted February 20, 1934.

25 As the top of the crate 75 approaches the 30 tuckers 125 the tucker rollers 130 come into contact with the lettuce extending above the crate so as to tuck this inwardly over the crate to a certain degree. After the box has come into contact with the rollers 130, however, the tuckers 35 125 are caused to swing about their pivotal axes on the bolts 127 so as to accomplish a secondary inward tucking operation on the endmost pieces of the top layer of lettuce. This is best illustrated in Fig. 5. At this point in the opera- 40 tion the cover 165 has been contacted by the lettuce and lifted upwardly against the bevelled faces 120 of the cover compressing bars 105 so that the cover is commencing to take an arcuate shape and is pressing the lettuce, which was just 45 tucked inwardly, downwardly into the crate 75. The completion of this series of operations is shown in Fig. 6, where the box 75 has been lifted upwardly to completely arch the cover 165 thus forcing the endmost rows of the upper layer of 50 lettuce downwardly into the crate.

55 As the upper end of the crate 75 extends upwardly beyond the axis about which the tucker 125 swings, the tucker roller 130 is expelled outwardly from between the box and the cover 165 so that the cover may come into contact with the box end and be nailed thereon as shown in Fig. 6. This figure also shows how the tucker arms 126 come up against the stops 122 so that the tucker rollers 130 will positively bear against 60 the box ends 76 and center the crate with respect to the cover 165 so that the cover will be properly positioned on the crate 75 when nailed thereto. Means is provided by which the operator, by depressing a pedal, may cause the drivers 65 91 to simultaneously drive nails through the cover 165 into the crate ends 76. Although not shown in this application, such means is well known in the art and representative means for this purpose may be seen in my Patent No. 1,947,917. In 70 said patent the control means is also arranged so that as soon as the box is lidded the conveyer 27 automatically moves downwardly and the box is ejected therefrom. When this takes place the rollers 130 merely roll over the ends of the cov-

ered crate, returning to the positions in which they are shown in Fig. 1.

From the foregoing description it is seen that I have provided an extremely simple lid applying and material tucking means which operates automatically and which centers the crate relative to the cover during the nailing of the cover thereto. It is also clear that this device cannot possibly cause serious accidental injury to the operator of a lidder in which the device is embodied.

In Fig. 7 I have shown a modified form of roller 180 which is adapted to take the place of the roller 130 in the mechanism above described. The roller 180 is formed in separate sections 181 and 182 which are separated by discs 183 of slightly larger diameter than the rollers 181 and 182. The roller is mounted upon a shaft 185 having end studs 186 which pass through suitable apertures in the tucker arms 126 and are secured rigidly thereto as by nuts 188. The advantage of the roller 180 is that the discs 183 extend beyond the periphery of the roller sections 181 and 182 so as to contact the upper end of a crate 75, thus permitting the roller sections 181 and 182 to rotate freely when in contact with the paper 160 covering the lettuce in the crate.

As the roller sections 181 and 182 comprise almost the entire surface of the roller 180, friction between the roller 180 and the paper 160 which might cause undue wrinkling of the latter is practically eliminated.

The term presser head when used in the claims broadly indicates that portion of the overhead structure which cooperates with the nailing table in pressing the lid upon a box resting on said table. The tucker support means or legs 121 are rigidly mounted on the presser head. While they are here shown in the form of depending legs, this support means may consist of any suitable structure for supporting the tuckers by connection with the tucker arm means 126 on axes disposed

outwardly away from over the box when the latter is positioned on the table for lidding.

It is desired to point out also, that while the tuckers 130 and the tucker arm means 126 are shown as separate mechanical elements in the disclosed embodiment, various modifications may be made in the structure of these elements without departing from the spirit of the invention or the scope of the appended claims.

What I claim is:

1. In combination: a box support; a lid presser head disposed thereabove; means for accurately positioning a box longitudinally on said box support; end tuckers normally disposed over end portions of said box when the latter is positioned as aforesaid; arm means extending outwardly from said tuckers when the latter are normally positioned; tucker support means rigidly mounted on said presser head, said tucker arm means being pivotally connected to said support means on axes disposed outwardly from over said box, inward and outward movement of said tuckers being limited substantially to those movements thereof which are occasioned by rotation of said arm means about said pivotal connections; and means causing relative movement between said head and said box support to press a lid on said box, said tuckers being actuated to tuck the overflow inwardly and then withdraw from over said box ends by engagement of said tuckers with said box and said overflow incidental to said relative vertical movement.

2. A combination as in claim 1 in which said arm means also extend upwardly in normal position from said tuckers to the axes of said pivotal connections.

3. A combination as in claim 1 having spring means to return said tuckers to their normal positions following a lid pressing operation.

HALE PAXTON.
